UNITED STATES PATENT OFFICE.

JOHN J. MAIER, OF ATLANTA, GEORGIA.

VENTILATOR.

937,254.

Specification of Letters Patent. Patented Oct. 19, 1909.

Application filed April 16, 1909. Serial No. 490,204.

To all whom it may concern:

Be it known that I, JOHN J. MAIER, citizen of the United States, residing at Atlanta, in the county of Fulton and State of Georgia, have invented certain new and useful Improvements in Ventilators, of which the following is a specification, reference being had therein to the accompanying drawing.

This invention relates particularly to cowls or hoods of sheet metal which are placed, usually above the roof of a building, upon the end of the ventilating pipe of factories and the like where the volume of air to be discharged is very large, and the pipe and hood correspondingly large. It is highly desirable that such a hood should be so constructed that rain is excluded, down-currents prevented, and the escape of air aided to an unusual degree, by winds, and further desirable that the hood, although large, should be light and at the same time strong and capable of strongly resisting distortion. The latter consideration is more important than it appears at a glance, for a large hood, often several feet in diameter, if made of thin sheet metal, for lightness, is very readily bent out of shape in handling and very difficult to restore to form when so bent.

The objects of this invention are to secure the advantages while avoiding the evils suggested, and at the same time to obtain certain gains in convenience and cost of manufacture.

In the accompanying drawings, Figure 1 is a side view, partly in axial section, of devices embodying my invention. Fig. 2 is a vertical section of a certain ring. Fig. 3 is a central horizontal section of a portion of the same ring. Fig. 4 is a side view of the joint in a certain shield member. Fig. 5 is a section on the line 5—5, Fig. 4. Fig. 6 is an elevation of a portion of a certain skirt.

In these views, A represents a pipe forming a part of, or adapted to fit closely, the ventilating pipe which usually projects above the roof of the building to be ventilated. From the upper end of the pipe A depends an outwardly diverging conical skirt B, and above this pipe is a ring C which is centrally constricted in such manner that its smallest diameter is slightly greater than that of the pipe while its diameter at both upper and lower margins is materially larger, the diameters gradually decreasing in passing toward the horizontal plane of the smaller part so that in cross-

section the wall is a curve as shown, and so that the lower divergent portion is approximately parallel to the skirt B. At some distance above the plane of the upper margin of the ring is a cone D of relatively slight altitude, with its vertex in the common axis of the pipe, skirt, and ring. Around the ring C is fixed a much larger annular shield E having the same axis, and the upper margin of which lies nearly in the plane of the base of the cone, while its lower margin lies in a plane some distance below the top of the pipe A. The ring, cone and shield are all rigidly held in fixed relation to the pipe and to each other by brackets F of suitable shape riveted to the several members. This general construction is shown in prior patents, and is not herein claimed.

The ring C is made up of a series of curved plates C, C' each having in vertical planes a series of small corrugations C² preferably not quite reaching the upper and lower margins of the plates, and the lateral marginal portions of the plates are pressed inward to form large ribs C³ which vary gradually from zero at the upper and lower margins of the plates to a maximum at the innermost point of the vertical curve of each plate. The large ribs of adjacent plates fit closely over one another and are preferably soldered together throughout their meeting surfaces. By their form and doubled thickness they give the ring extraordinary stiffness, and the parts being duplicates, individually of relatively small sizes, are very readily pressed into the desired form and united to form the ring. The outwardly projecting edges being uncorrugated yet supported by the tapered ribs strongly resist vertical bending, and the ring so formed resists force applied in any direction and tending either to distort the ring, as a whole, from plane or circular form, or to bend any individual portion thereof, and the large and deep grooves and ribs also serve to aid materially in deflecting winds upwardly, and thereby strengthen the current which tends to exhaust air from the upper end of the pipe A and still further to lessen the whirling movement of the air about the axis of the pipe due to the tendency of the air upon each side of the radial line of the wind's direction to pass around the pipe horizontally.

The cone D is made from a plane sheet disk by forming therein, at short circum-

ferential intervals, radial ribs D' which gradually increase in width in passing outward, and thereby the disk is made conical and at the same time greatly stiffened and 5 protected.

The shield E is, in general form, a short cylinder provided with large circumferential corrugations or ribs E' and it is formed from a strip of uniform width bent to 10 proper form and having its end portions cut to form longitudinal fingers E² which, in joining the ends, pass alternately within and without the metal of the companion end and are riveted or soldered thereto, or both 15 riveted and soldered, thereby securing a union which offers very great resistance to displacement of the parts in any direction whatever. In fact, without solder or rivets, the joint is rigid and the parts can move 20 only longitudinally.

The lower margin of the skirt B is pressed into the form of an annular rib B², its inclined body portion is passed outward to form a series of half cones B³ having the 25 vertexes at the rib, its upper marginal portion is bent to vertical position between the cones, the surplus stock being folded over at B⁴, the part above the cones is bent downward to form a vertical flange, fitting the interior of the pipe, the upper end of which is thus held between the two vertical portions of the skirt and reinforced terminally as 30 well as within and without. The exterior vertical portion of the skirt is integrally 35 united throughout nearly its entire width with the large end of the rib which is integral with and extends across the oblique portion, vanishing near the margin thereof. Thus the vertical and oblique portions of the 40 skirt are rigidly held at a fixed angle with each other, the edge of the skirt is held against vertical bending by the ribs, which do not reach and corrugate it. The whole 45 rigid skirt member holds the very large and thin end of the pipe in circular form, whereby it better sustains the shield, ring, and cone. It is also obvious that these large ribs in radial vertical planes strongly tend to 50 deflect the air upwardly and to resist its passing around the pipe horizontally, in this co-acting with the ribs of the ring above.

What I claim is:

1. The combination with an open ventilating pipe, of a concentric, horizontal, centrally constricted ring fixed above the end 55 of the pipe, projecting beyond its walls, and provided with large inwardly projecting

vertical ribs at some distance apart; whereby the whirling tendency of air currents striking the ring laterally is lessened.

60

2. The combination with an open ventilating pipe provided with a skirt diverging downwardly from its upper end and having upon its upper side radial ribs, of a concentric, horizontal, centrally constricted ring 65 above the end of the pipe, projecting beyond its walls, and provided between its margins with inwardly projecting ribs in radial planes and at some distance from each other; whereby the tendency of horizontal air currents 70 to pass around the axis of the pipe is resisted by the skirt below and the ring above.

70

3. In apparatus of the class described, the combination with an open ventilating pipe, 75 of a horizontal, concentric, centrally constricted ring above the end of the pipe and provided at intervals with heavy inwardly projecting radial ribs the projection of which gradually increases from zero at the margin 80 of the ring to a maximum near its medial horizontal plane.

80

4. In apparatus of the class described, the combination with an open ventilating pipe and air deflecting devices above the end of 85 the same, of an upwardly converging skirt having a doubled, cylindrical upper end portion adapted to fit the interior and exterior 90 of the pipe wall, and a series of adjacent ribs, in radial planes, pressed out from the body of the metal and having their outer elements extending approximately from the upper to the lower margin of the skirt.

90

5. The combination with an open vertical 95 ventilator pipe and an air deflecting device above its end, of a conical sheet metal skirt having at its smaller upper end an integral vertical portion fitting, collar-like, the upper end of the pipe, said skirt being provided upon its upper side with radial stiffening and 100 air-deflecting ribs integral with both the body of the skirt and said vertical portion and gradually increasing in projection, from said body, from zero at the skirt's lower margin to approximately the width of said 105 vertical portion at the point where it meets the latter.

105

In testimony whereof I affix my signature in presence of witnesses.

JOHN J. MAIER.
